UNITED STATES PATENT OFFICE.

GARTH GRIFFITH GILPIN, OF RIVERSIDE, ILLINOIS, ASSIGNOR OF ONE-HALF TO
CHARLES B. YOUNG, OF AURORA, ILLINOIS.

VENTILATOR.

1,264,291.

Specification of Letters Patent.

Patented Apr. 30, 1918.

Application filed February 7, 1916. Serial No. 76,845.

To all whom it may concern:

Be it known that I, GARTH GRIFFITH GILPIN, a citizen of the United States, residing at Riverside, in the county of Cook and State of Illinois, have invented a certain new and useful Improvement in Ventilators, of which the following is a description, reference being had to the accompanying drawing, which forms a part of my specification.

10 My invention relates to ventilators more especially adapted for railway cars and the like; and has for its object the provision of a construction wherein the drafts or outer currents of air are utilized to induce a suction in the outlet or discharging passage of the ventilator which causes the vitiated air to be withdrawn from the car-interior.

15 A further object of the invention is to provide a construction whereby the air-currents, regardless of their normal direction, will be caused to flow in such manner as to provide an effective degree of suction; and whereby rain, cinders, and other foreign matter, will be prevented from entering the 20 car-interior through the ventilator.

The objects of my invention, as well as the advantages inherent in the construction, will be more fully understood from the following detailed description of the accompanying 30 drawing, wherein:—

Figure 1 is a perspective view of a portion of a car-roof, showing the application of my improved ventilator which is shown in vertical section.

35 Fig. 2 is a top plan and sectional view of my improved ventilator.

Fig. 3 is a vertical sectional view of a modified form.

Fig. 4 illustrates another modified form in 40 elevation.

In the particular exemplification of my invention, the ventilator is shown applied to the usual ventilator window or opening of the clearstory of a monitor type of car-roof so as to provide considerable clearance between the bottom of the ventilator and the lower deck of the roof, the usual window-opening being shown at 5 in Fig. 1 arranged in the sides of the clearstory; the ventilator 45 being either secured in the opening or adjacent thereto as shown,

The ventilator in its preferred form comprises a metallic housing having one side wall 6 and two end walls 7, 7. The housing is provided with the attaching flange-portions 8, preferably made integral with the two end walls 7, 7 and also made continuous so as to extend from end wall to end wall along the top and bottom of the construction. The side adapted to be secured against 55 the clearstory of the car-roof is preferably entirely open, thus providing a comparatively large inlet or opening for the passage of air from the car-interior. The ventilator is preferably made of dimensions sufficient 60 to incase or entirely surround the window-opening in the clearstory of the roof, so as to afford unobstructed communication with the car-interior.

The ventilator is preferably formed without a top or a bottom, as clearly shown in Figs. 1 and 2, thereby providing large exhaust openings for the passage of the vitiated air withdrawn from the car-interior through the action of the air-currents passing 70 across the upper and lower edges of the windward or air-impinging wall or side of the housing.

In order to prevent rain, snow, cinders and other foreign matter entering the car-interior through the top or bottom of the ventilator, I provide the deflecting members 9 and 10 at the top and bottom, respectively. The deflector 9 at the top is shown integral with, or otherwise secured to the longitudinally disposed attaching flange 8 immediately above the car-communicating opening, and is arranged to extend downwardly intermediate of the end walls, the deflector being 80 preferably materially larger or of greater 85 width than lower deflector 10.

Deflector 10 is formed integral with, or otherwise secured to, the lower longitudinally disposed attaching flange 8, see Fig. 1. The lower deflector 10 curves slightly upwardly toward its outer edge, as shown in Fig. 1, so that any cross-currents of air, as well as snow, rain, and other foreign substance, which are forced against the lower deck or adjacent the clearstory beneath the 95 ventilator will be deflected downwardly and away from the opening communicating with 100

the car-interior and therefore prevented from entering through the window-opening in the car-roof. The deflectors 9 and 10 are both so formed to extend intermediate of the 5 horizontal planes occupied by the upper and lower edges of the side and end walls; in other words the deflectors do not project beyond the outer walls or air-impinging surfaces. The deflectors 9 and 10 are so disposed that a considerable space or opening 10 will be left intermediate of the unattached edges thereof, so as to provide a comparatively large space for the free egress of the vitiated air from the car-interior through 15 the eduction or exhausting action caused by the outer air-currents.

With the ventilator secured adjacent the opening in the clearstory of the roof so as to provide the clearance between the 20 ventilator and the lower deck of the roof of the car, it is apparent that the ventilator will permit the foul air of the car to be withdrawn either through the bottom of the ventilator or through the top thereof, which, in 25 the preferred construction, are left practically entirely open, except in so far as the deflectors 9 and 10 are concerned.

The two end walls 7, 7 and the side wall 6 are preferably made flat and provided with 30 the horizontally disposed upper and lower edges which will induce the air-currents impinging against said walls to pass about said edges and across the openings in the top and bottom of the ventilator and thereby 35 create an eduction action or suction in the ventilator which will cause air to be withdrawn from the interior of the car through the open side and between the widely separated deflectors 9 and 10.

40 As illustrated in the drawing, the walls 7, 7, which I have termed the end walls, are disposed substantially at right angles to the longitudinal axis of the car, so that movement of the car, in either direction, will 45 cause the air to impinge against the forwardly presented end wall and be directed across the open top and bottom and thereby cause a suction or eduction action in the ventilator as described.

50 In the event that the outer air-currents should be cross-wise or in a direction transversely to the car, the air will impinge against the side wall 6, and its passage over the edges of the side wall will likewise cause 55 the vitiated air of the car to be withdrawn therefrom and forced to flow through the discharge openings of the ventilator.

Where the air-currents are in a downward direction, they will impinge against the 60 downwardly sloping surface of deflector 9 and be caused to flow through the ventilator and be discharged at the bottom; and in view of the fact that deflector 10 is made shorter than deflector 9, the air-currents, 65 through the ventilator as just described, will

not be interrupted or in any way interfered with.

Any downward air-currents that may impinge against the wall or side 6 and pass over the lower edge thereof will assist the action of those passing downwardly through the ventilator, and by reason of the curvature of deflector 10 will be caused to flow about the end walls of the structure and also toward the lower deck of the roof, and therefore prevented from passing upward through the eduction or communicating-opening in the side of the ventilator and into the car.

70 In Fig. 3, I show a modified form of the 80 ventilator, which, in general construction, is identical with the construction shown in Figs. 1 and 2, the modification comprising a number of louvers or baffle members 11 arranged intermediate of the deflectors 9 and 10 and extending from end wall to end wall; the louvers being preferably arranged in 75 staggered relation to each other as disclosed in Fig. 3, so as to provide sufficient openings intermediate of the longitudinal edges of 85 the louvers or baffle members and the deflectors 9 and 10. I have shown the construction disclosed in Fig. 3 provided with the three baffles or louvers, but it is apparent that any suitable number may be employed 90 which will prevent foreign substance being forced through the open side or car-communicating opening of the ventilator through the action of any cross currents 95 that may impinge against the car-roof beneath the ventilator, especially when the 100 car is in rapid motion.

105 In Fig. 4, I show another form of my improved ventilator, (that shown in the preceding figures being, however, the preferred form) wherein the walls 7^a, 7^a, which I have 110 termed end walls, are swelled outwardly, somewhat in the nature of a horizontally disposed V, in cross-section; the general construction of the ventilator, however, being identical with the construction previously 115 described and shown in Figs. 1 and 2.

I have shown and described these embodiments of my invention, but modifications in certain respects may be made without, however, departing from the spirit of my invention, and I do not wish to be understood therefor as limiting myself to the exact construction shown and described.

120 What I claim is:—

1. In a car ventilator, the combination of a structure having end walls and a side wall connecting the end walls, said structure being open at the top and bottom and at the side opposite said side wall and being provided with means whereby it may be secured to the exterior of a car with its open side communicating with the interior thereof and its end walls, substantially transverse to the line of travel of the car, a deflecting 125

- member extending downwardly and outwardly from the top of the open side of said structure and from one end wall to the other; and a deflecting member extending in 5 a curve outwardly and upwardly from the bottom of said open side and from one end wall to the other; said deflecting members dividing the interior of the ventilator into two unobstructed spaces in communication 10 through a gap between said members, the inner of which spaces opens directly and unobstructedly into the car and the outer of which opens at top and bottom unobstructedly into the outside atmosphere.
- 15 2. In a car ventilator, the combination of a structure having end walls and a side wall connecting the end walls, said structure being open at the top and bottom and at the side opposite said side wall and being provided with means whereby it may be secured to the exterior of a car with its open side 20 communicating with the interior thereof and its end walls, substantially transverse to the line of travel of the car; and deflecting 25 members extending outwardly from the top and bottom respectively, of the open side of said structure and from end wall to end wall so that a gap intervenes between their outer edges; one of said deflecting members having 30 an inclination toward the other; said deflecting members dividing the interior of the ventilator into two unobstructed spaces communicating through said gap, one of said spaces opening directly and unobstructedly 35 into the car and the other opening at top and bottom unobstructedly to the outside atmosphere.
3. In a car ventilator, the combination of a structure having end walls and a side 40 wall connecting the end walls, said structure being open at the top and bottom and at the side opposite said side wall and being provided with means whereby it may be secured to the exterior of a car with its open 45 side communicating with the interior thereof and its end walls, substantially transverse to the line of travel of the car, a deflecting member extending downwardly from the top of the open side of said structure and from 50 one end wall to the other; and a deflecting member extending outwardly from the bottom of said open side and from one end wall to the other, one of said members having an inclination toward the other; said deflecting 55 members dividing the interior of the ventilator into two unobstructed spaces in communication through a gap between said members, the inner of which spaces opens directly and unobstructedly into the car and the outer of which opens at top and bottom unobstructedly into the outside atmosphere, and louvers arranged in the gap between said deflecting members which extend from end wall to end wall.
- 60 4. In a car ventilator, the combination of a structure having end walls and a side wall connecting the end walls, said structure being open at the top and bottom and at the side opposite said side wall and being provided with means whereby it may be secured to the exterior of a car with its open side 65 communicating with the interior thereof and its end walls substantially transverse to the line of travel of the car; a deflecting member extending downwardly and outwardly from the top of the open side of said structure and from end wall to end wall, and a deflecting member extending out-
- connecting said end walls; said structure being open at the top and bottom and at the side opposite said side wall and being provided with means whereby it may be secured to the exterior of a car with its open 70 side communicating with the interior thereof and its end walls, substantially transverse to the line of travel of the car; a deflecting member extending outwardly from the bottom of the open side of said ventilator and from end wall to end wall thereof; and a deflecting member extending downwardly and outwardly from the top of said opening and from end wall to end wall, the last mentioned deflecting member projecting outwardly beyond the other deflecting member; said deflecting members dividing the interior of the ventilator into two unobstructed spaces in communication through a gap between said members, one of said spaces opening directly and unobstructedly into the car and the other opening at top and bottom unobstructedly to the outside atmosphere.
- 75 5. In a car ventilator, the combination of a structure having end walls and a side 80 wall connecting said end walls, said structure being open at the top and bottom and at the side opposite said side wall and being provided with means whereby it may be secured to the exterior of a car with its open 85 side communicating with the interior thereof and its end walls, substantially transverse to the line of travel of the car; a deflecting member extending outwardly from the bottom of the open side of said ventilator and from end wall to end wall thereof; and a deflecting member extending downwardly and outwardly from the top of said opening and from end wall to end wall, the last mentioned deflecting member projecting outwardly beyond the other deflecting member; said deflecting members dividing the interior of the ventilator into two unobstructed spaces in communication through a gap between said members, one of said spaces opening directly and unobstructedly into the car and the other opening at top and bottom unobstructedly to the outside atmosphere.
- 90 6. In a car ventilator, the combination of a structure having end walls and a side 95 wall connecting said end walls, said structure being open at the top and bottom and at the side opposite said side wall and being provided with means whereby it may be secured to the exterior of a car with its open 100 side communicating with the interior thereof and its end walls, substantially transverse to the line of travel of the car; a deflecting member extending outwardly from the bottom of the open side of said ventilator and from end wall to end wall thereof; and a deflecting member extending downwardly and outwardly from the top of said opening and from end wall to end wall, the last mentioned deflecting member projecting outwardly beyond the other deflecting member; said deflecting members dividing the interior of the ventilator into two unobstructed spaces in communication through a gap between said members, one of said spaces opening directly and unobstructedly into the car and the other opening at top and bottom unobstructedly to the outside atmosphere, and louvers arranged in the gap between said deflecting members which extend from end wall to end wall.
- 105 7. In a car ventilator, the combination of a structure having end walls and a side 110 wall connecting the end walls, said structure being open at the top and bottom and at the side opposite said side wall and being provided with means whereby it may be secured to the exterior of a car with its open side communicating with the interior thereof and its end walls substantially transverse to the line of travel of the car; a deflecting member extending downwardly and outwardly from the top of the open side of said structure and from end wall to end wall, and a deflecting member extending out-
- 115 8. In a car ventilator, the combination of a structure having end walls and a side 120 wall connecting the end walls, said structure being open at the top and bottom and at the side opposite said side wall and being provided with means whereby it may be secured to the exterior of a car with its open side communicating with the interior thereof and its end walls substantially transverse to the line of travel of the car; a deflecting member extending downwardly and outwardly from the top of the open side of said structure and from end wall to end wall, and a deflecting member extending out-
- 125 9. In a car ventilator, the combination of a structure having end walls and a side 130 wall connecting the end walls, said structure being open at the top and bottom and at the side opposite said side wall and being provided with means whereby it may be secured to the exterior of a car with its open side communicating with the interior thereof and its end walls substantially transverse to the line of travel of the car; a deflecting member extending downwardly and outwardly from the top of the open side of said structure and from end wall to end wall, and a deflecting member extending out-

wardly from the bottom of said open side and from end wall to end wall; said deflecting members dividing the interior of the ventilator into two unobstructed spaces 5 in communication through a gap between said members, one of said spaces opening directly and unobstructedly into the car and

the other opening at top and bottom unobstructedly to the outside atmosphere.
